United States Patent Office

Des. 224,862
Patented Oct. 3, 1972

224,862

CHAIR

Thomas Winrow, Naperville, Ill., assignor to Futorian Corporation, Amsterdam, N.Y.

Filed Dec. 7, 1970, Ser. No. 26,322

Term of patent 14 years

Int. Cl. D6—02

U.S. Cl. D6—73

The figure is a perspective view of a chair illustrating my new design. The back of the chair is conventionally plain while the side not shown is substantially identical to the side shown.

I claim:

The ornamental design for a chair, substantially as shown and described.
